his Attorney

UNITED STATES PATENT OFFICE.

CAMERON A. REED, OF BROOKLYN, NEW YORK.

RAILWAY-TRAFFIC-CONTROLLING APPARATUS.

Application filed April 24, 1928. Serial No. 272,377.

My invention relates to railway traffic controlling apparatus, and particularly to apparatus of the type involving signals, switches, etc., controlled by the manually operable levers of an interlocking machine.

I will describe one form of apparatus embodying my invention, and will then point out the novel features thereof in claims.

The accompanying drawing is a diagrammatic view showing one form of apparatus embodying my invention.

Referring to the drawing, the reference characters 1 and 1^a designate the track rails of a railway track over which traffic moves in both directions. These rails are divided by insulated joints 2 to form track sections, of which only one section D—E is shown in the drawing. Section D—E is provided with two signals S^R and S^L for governing traffic through the section in opposite directions, and it is also provided with two automatic stop devices A^R and A^L associated with the two signals S^R and S^L, respectively. Each of these stop devices normally occupies its active position wherein it will operate to apply the brakes of a passing train, but when the device is energized it is moved to its inactive position wherein it has no effect on a passing train.

Associated with the stop device A^R is a stop control relay C^R, and associated with the stop device A^L is a similar stop control relay C^L.

Section D—E is provided with a track circuit comprising a track battery 3 connected across the rails at one end of the section and a track relay T connected across the rails at the other end of the section.

The signals S^R and S^L are controlled by a manually operable lever L, which will usually be one of a plurality of levers in an interlocking machine. This lever normally occupies its middle or normal position, but may be swung to a right-hand position or a left-hand position, wherein it functions to clear signal S^R or signal S^L as hereinafter explained.

The stop control relay C^R is provided with a pickup circuit which passes from terminal B of a suitable source of current, through contact 31 of track relay T, wire 22, and winding of relay C^R to terminal O of the same source of current. This relay is provided with a stick circuit which passes from terminal B, through contact 7 of lever L,

wires 25 and 26, front contact 8 of relay C^R, and the winding of relay C^R to terminal O. Contact 7 is closed when the lever L is in its normal position or its right-hand position or any position between the two. Relay C^R is provided with a pickup circuit which passes from terminal B, through contact 32 of track relay T, and the winding of relay C^L to terminal O. This relay is provided with a stick circuit which passes from terminal B, through contact 6 of lever L, wires 23 and 24, front contact 12 of relay C^L, and the winding of relay C^L to terminal O. Contact 6 is closed while lever L is in its normal position or its left-hand position or any position between the two.

The circuit for signal S^R is from terminal B, through front contact 9 of relay C^R, wire 18, front contact 13 of relay C^L, wire 19, contact 5 of lever L, wire 20 and the operating mechanism of signal S^R to terminal O. Contact 5 is closed when and only when lever L is in its right-hand position. The circuit for signal S^L is the same as the circuit just traced up to and including wire 19, and it then passed through contact 4 of lever L, wire 21 and the operating mechanism of signal S^L to terminal O. Contact 4 is closed when and only when lever L is in its left-hand position.

The stop device A^R is provided with a normal circuit which passes from terminal B, through contact 16 and the operating mechanism of the stop device to terminal O. Contact 16 is closed when and only when signal S^R is in the proceed position. The stop device A^R is provided with an auxiliary circuit which passes from terminal B, through back contact 11 of relay C^R, wire 29, and the operating mechanism of the stop device to terminal O. The stop device A^L is provided with a similar normal circuit which includes contact 17 operated by signal S^L, and with a similar auxiliary circuit which includes back contact 15 of relay C^L and wire 30.

The operation of the apparatus thus far described, is as follows: As shown in the drawing, lever L is in its normal position, and track relay T is energized so that stop control relays C^R and C^L are both energized. Both signals are at stop, and both stop devices A are in their active positions. Assuming that a train moving toward the right is about to enter section D—E, the operator will swing lever L to its right-hand position,

thereby closing at contact 5 the circuit for signal S^R , so that this signal will move to the proceed position. The main circuit for stop device A^R is then closed at contact 16, 5 so that this stop device moves to its inactive position. The stick circuit for relay C^R remains closed at contact 7 of lever L, but the stick circuit for relay C^L is opened at contact 6. Relay C^L remains energized, however, until the train enters section D—E. 10 When the train does enter this section, track relay T will open, thereby opening the pickup circuits for both relays C^R and C^L . Relay C^R will remain energized by virtue of its stick circuit, but relay C^L will become de-energized because its stick circuit is open. The circuit for signal S^R is now open at contact 13 of relay C^L , so that this signal goes to the stop position, and stop device 15 A^R returns to its active position. When the operator returns lever L to its normal position, it will have no effect on the apparatus. The auxiliary circuit for stop relay A^L is now closed at back contact 15 of relay C^L , so 20 that this stop device is in the inactive position, and so it will have no effect on the train as the train leaves section D—E. When the entire train has passed out of section D—E, track relay T will again become energized so that relay C^L will become energized, with the result that stop device A^L 25 will return to its active position.

When a train moving toward the left is about to enter section D—E, the operator 30 will swing lever L to the left, thereby closing the circuit for signal S^L and so the main circuit for stop device A^L . As the train enters section D—E and de-energizes track relay T, relay C^L will remain energized, because its stick circuit is closed at contact 6 of lever L, but relay C^R will become de-energized because its stick circuit is open at contact 7. The auxiliary circuit for stop device A^R is therefore closed at contact 11 of 35 relay C^R , so that this device will be in its inactive position when the train passes it.

I will now assume that the operator has moved lever L to its right-hand position to permit a train moving toward the right to 40 pass through section D—E, and that while such train is in the section the operator returns lever L but inadvertently moves it beyond the normal position. This would result in momentarily opening the stick circuit for relay C^R at contact 7, so that this relay would become de-energized and would remain de-energized as long as its pickup circuit is open at track relay T due to the presence of the train in the section. Relay 45 C^R being de-energized, the auxiliary circuit for the stop device A^R would be closed at contact 11, and so this stop device would improperly be in its inactive position while section D—E is occupied by a train moving 50 toward the right. Similarly, while a train

moving toward the left is in section D—E, if the operator inadvertently returns lever L to a point beyond its normal position, the stick circuit for relay C^L would be opened at contact 6 and the stop device A^L would assume 55 its inactive position. To prevent such improper operations of the stop device, I have provided an auxiliary stick circuit for each relay C^R and C^L . The auxiliary circuit for relay C^R is from terminal B through back 60 contact 14 of relay C^L , wires 27 and 26, front contact 8 of relay C^R and the winding of relay C^R to terminal O. The auxiliary stick circuit for relay C^L is similar, in that it includes back contact 10 of relay C^R and 65 wires 28 and 24. Again assuming that a train moving toward the right is in section D—E, and that the operator inadvertently swings lever L beyond its normal position in attempting to return it to its normal position, relay C^R will remain energized, because its auxiliary stick circuit is closed at back contact 14 of relay C^L , and so the auxiliary circuit for the stop device A^R will remain open. Similarly, when a train moving 70 toward the left occupies section D—E and the operator attempts to return lever L from its left-hand position to its normal position, if he inadvertently moves the lever beyond the normal position relay C^L will remain energized by virtue of its auxiliary 75 stick circuit through back contact 10 of relay C^R .

As shown in the present disclosure, each 80 relay C^R and C^L controls an automatic stop device, but it is understood that my invention is not limited to a device of this nature, and that any suitable railway traffic controlling device may be controlled by these relays without departing from the scope of my 85 invention.

It will be observed that when either of the 90 stop control relays C^R or C^L is de-energized, the associated stop device A^R or A^L will be in its inactive position. It is important, therefore, to insure that both of these relays are 95 energized when a train is about to enter section D—E, and for this reason I have included front contact 9 of relay C^R and front 100 contact 13 of relay C^L in the circuit for each of the signals S^R and S^L . It will be seen that this provision guarantees that both of the 105 relays are energized before a signal can be cleared to permit a train to enter section D—E.

Although I have herein shown and described only one form of apparatus embodying my invention, it is understood that various changes and modifications may be made therein within the scope of the appended 115 claims without departing from the spirit and scope of my invention.

Having thus described my invention, what I claim is:

1. In combination, a section of railway 120

- track, two signals S^R and S^L for governing traffic in opposite directions through said section, two automatic stop devices A^R and A^L associated with said two signals respectively, 5 and each arranged to be inactive when energized, two stop control relays C^R and C^L associated with said two signals respectively, a signal lever for the control of said signals, a track circuit including a track relay for 10 said section, a pick-up circuit for each stop control relay including a front contact of said track relay, a stick circuit for relay C^R including a normal-to-right contact of said lever, a stick circuit for relay C^L including 15 a normal-to-left contact of said lever, means for causing signal S^R or signal S^L to indicate proceed according as said lever is moved to its right-hand or its left-hand position, means for energizing each stop device when 20 the associated signal indicates proceed, means for energizing each stop device when the associated stop control relay is de-energized, an auxiliary stick circuit for relay C^R including 25 an back contact of relay C^L , and an auxiliary stick circuit for relay C^L including a back contact of relay C^R .
2. In combination, a section of railway track, two signals S^R and S^L for governing traffic in opposite directions through said section, two automatic stop devices A^R and A^L associated with said two signals respectively, 30 and each arranged to be inactive when energized, two stop control relays C^R and C^L associated with said two signals respectively, a signal lever for the control of said signals, a track circuit including a track relay for 35 said section, a pick-up circuit for each stop control relay including a front contact of said track relay, a stick circuit for relay C^R including a normal-to-right contact of said lever, a stick circuit for relay C^L including a normal-to-left contact of said lever, means for energizing device A^R when the said lever is moved to its right-hand position and energizing device A^L when the said lever is moved to its left-hand position, other means 40 for energizing each device when the associated control relay is de-energized, an auxiliary stick circuit for relay C^R including a back contact of relay C^L , and an auxiliary stick circuit for relay C^L including a back 45 contact of relay C^R .
3. In combination, a section of railway track, two signals for governing traffic in opposite directions through said section, 50 two automatic stop devices associated with said two signals respectively, a signal lever, means operating when said lever is swung 55 in one direction or the other from its normal position to clear one signal or the other and to place in inactive condition the stop device associated with the signal which is cleared, means operating while said section is occupied to place the stop device at the exit end in inactive condition, and means for preventing the stop device in the rear 60 of a train occupying said section from being placed in inactive condition if the operator inadvertently swings said lever beyond the normal position while restoring it to normal 65 position.
4. In combination, a section of railway track over which traffic moves in both directions, two traffic governing devices A^R and A^L located at the two ends of said section respectively and each arranged to prevent 70 traffic into the section unless energized, two control relays C^R and C^L associated with said two devices respectively, a lever for the control of said devices, a track circuit including a track relay for said section, a pick-up circuit for each of said control relays including a front contact of said track relay, a stick circuit for relay C^R including 75 a normal-to-right contact of said lever, a stick circuit for relay C^L including a normal-to-left contact of said lever, means for energizing device A^R when the said lever is moved to its right-hand position and energizing device A^L when the said lever is moved to its left-hand position, other means 80 for energizing each device when the associated control relay is de-energized, an auxiliary stick circuit for relay C^R including a back contact of relay C^L , and an auxiliary stick circuit for relay C^L including a back 85 contact of relay C^R .
5. In combination, a section of railway track over which traffic moves in both directions, two traffic governing devices located 90 at the two ends of the section respectively and each arranged to prevent traffic into the section unless energized, a lever having a normal position and capable of moving in opposite directions therefrom, means operating when said lever is moved in one direction or the other from its normal position to energize one of said traffic governing devices or the other, means operating while said section is occupied to energize the other of said traffic governing devices, 95 and means for preventing energization of the traffic governing device in the rear of a train occupying said section if the operator inadvertently moves said lever beyond the normal position while attempting to restore it 100 to normal position.

In testimony whereof I affix my signature.

CAMERON A. REED.
